RADIO RECEIVER

Harry Grayson, London, England, assignor to
 Baird Television Limited, London, England, a
 British Company

Application May 18, 1939, Serial No. 274,354
 In Great Britain December 12, 1938

2 Claims. (Cl. 250—20)

This invention relates to improvements in radio receivers and is especially concerned with a receiver adapted to be fed with signals from a balanced or coaxial feeder.

An object of the present invention is to obviate the necessity for switching in the aerial circuit when the receiver is required to operate on a waveband other than that to which the aerial connected to the said feeder is appropriate.

According to the present invention there is provided a radio receiver adapted to be fed with signals from a twin or coaxial feeder in which the earthy point of said feeder is connected to earth and to the grid circuit of a valve of the receiver through condensers.

In order that the present invention may be more particularly described reference is now made to the accompanying diagrammatic drawing which illustrates by way of example part of a radio receiver according to the present invention.

In the drawing a dipole aerial 1 is connected by means of a balanced feeder 2 to an inductance 3 in the receiver. The inductance 3 has its centre point returned to the earth line through a condenser 4 and this point is also connected through a further condenser 5 and a tuned circuit 6 to the grid of a valve 7. The grid of the valve 7 is returned to the earth line through a resistance 8. Coils 9 and 10 are arranged to be connected between the grid of the valve 7 and earth by means of switches 11 and 12.

The operation of the circuit is as follows. When the switches 11 and 12 are open signals received on the dipole 1 are fed through the coil 3 to the tuned circuit 6 and thus applied to the grid of the valve 7, the condensers 4 and 5 being such that they offer a low impedance at the frequency to which the circuit 6 is tuned. When either of the switches 11 or 12 is closed the appropriate coil 9 or 10 is tuned by condensers 4 and 5 in series to a frequency at which the inductance of the tuned circuit 6 is negligible.

When a shielded twin or a coaxial feeder is employed, the outer or shielding conductor is connected to the junction of the condensers 4 and 5.

The present invention is especially applicable to receivers adapted to receive signals in the television waveband as well as a number of pre-

selected stations in the broadcast band. In this case the dipole 1 and tuned circuit 6 are tuned to the television waveband while the coils 9 and 10 are such as to be tuned by the condensers 4 and 5 to frequencies in the broadcast waveband. For example, the valve 7 may be adapted to amplify both sound and vision frequencies in a television system; the aerial 1 and tuned circuit 6 being arranged to resonate at say 45 megacycles. The shunt capacity of the tuned circuit 6 may in this case be the stray circuit capacity and the input capacity of the valve 7. The condenser 4 would in this case be some 100–200 micromicrofarads while the condenser 5 would be adjustable and of the order of 100 10 micromicrofarads. The inductances 9 and 10 are preferably made variable and such as to be tuned by the condensers 4 and 5 in series to wave-lengths between 200 and 500 metres. It is also desirable to shunt the tuned circuit 6 by a 15 resistance 13 in order to flatten its response curve sufficiently to cover the wide frequency band necessary for television reception.

It is, of course, possible otherwise to vary the circuit arrangement shown.

I claim:

1. A radio receiver arranged to be fed with high frequency signals from a twin or coaxial feeder comprising a valve having a grid circuit, means including condensers for connecting the earthy point of said feeder to earth and to said grid circuit, a first inductance arranged to be supplied with high frequency signals from said feeder, a second inductance inductively coupled with said first inductance and connected at one end to said grid circuit and at the other end through said condensers to earth, means in shunt therewith for tuning said second inductance to said high frequency, at least a third inductance, and means for selectively connecting said third inductance between the grid circuit and earth.

2. A radio receiver according to claim 1 and in which a fourth inductance is provided with means for selectively connecting it in parallel with the third inductance, the third and fourth inductances being such that with said condensers in series they may be tuned to wavelengths between 200 and 500 metres.

HARRY GRAYSON. 50
